UNITED STATES PATENT OFFICE.

JOSEPH G. NOYES, OF MILFORD, CONNECTICUT, ASSIGNOR TO THE NATIONAL ELECTRICAL MANUFACTURING COMPANY, OF SAME PLACE.

DESIGN FOR A BRACKET.

SPECIFICATION forming part of Design No. 25,868, dated August 4, 1896.

Application filed June 10, 1896. Serial No. 595,036. Term of patent 14 years.

To all whom it may concern:

Be it known that I, JOSEPH G. NOYES, a resident of Milford, New Haven county, State of Connecticut, have invented and produced 5 a new and original Design for a Bracket, of which the following is a specification.

The leading feature of my design is a bracket of substantially the configuration represented in the accompanying drawing.

10 In the drawing, 1 indicates a perforated curvilinear shank terminated at one end by the ear 2 and at the other end by a slotted

yoke-shaped partition 3, from which rise angular arms 4 5.

What I claim is—

15 The design for a new, useful, original and ornamental article of manufacture, to wit: a bracket of substantially the configuration herein described and represented in the accompanying drawing.

JOSEPH G. NOYES.
